GEORGIANA S. GIFFORD, OF OCEAN GROVE, NEW JERSEY

COMBINED LEAF TURNER AND BOOKMARK

Application filed June 30, 1931. Serial No. 547,805.

This invention relates to an improved leaf turner that is adapted to be fitted around a thumb or finger and is quickly and easily attached or detached. The turner is provided on one face with a friction surface.

The object of the invention is to provide a leaf turner which is adapted for use as a leaf turner and in addition to this use can be used as a book mark. A strand used to secure the article on the finger also serves as an indicator when depending from between the leaves of a book. The strand can also serve to support a pendant which not only is an ornament and keeps the strand taut as a book mark but also engages a hook or other similar fixture on the pad to prevent the strand from slipping and thus keeps the pad in place on the finger.

The invention is illustrated in the accompanying drawings in which Figure 1 is a perspective view of the device secured to a finger. Figure 2 is a front view of the device removed from the finger in which form it is adapted for use as a book mark. Figure 3 is a central section of the pad of the device.

The pad 10 is flexible and I find soft rubber excellent material for its friction quality. In any event, the outer face 11 of the pad is a friction surface that will engage thin paper leaves or sheets and cause the top one to be moved or turned without the usual moistening of the engaging finger.

The pad 10 is provided with hooks 12 or similar fixtures at opposite sides. In the form shown I secure the hooks 12 to a backing 13 by rivets 14 and the main part of the pad is secured to the backing, usually by means of an adhesive. It will be evident, however, that the pad can be made of one piece of material.

The strand 15 is secured at one end to one of the hooks 12 and is used as shown in Figure 1 when the pad is secured to a finger. The hooks are placed with their ends directed inwardly and the strand 15 is caught over first one and then the other to secure the pad in place. The pendant 16 can be a tassel or any other form of ornamental end piece and as an enlargement it serves to hold the strand 15 from passing through a hook 12. This

prevents loosening of the pad on the finger. The pad is usually made of elastic material which aids in keeping the strand taut and under tension when in use as a fastening means.

The strand also serves as an indicator when it projects from between the pages of a book in which the pad 10 is placed. The pad is held against accidental removal or displacement by reason of its friction surface engaging the page of the book and when the book is closed the pad is secure against sliding down and the strand remains projecting from the book. The pendant 16 serves as a weight to keep the strand straight and the strand is not apt to be caught on outside objects and is less apt to be snarled or knotted.

The device can be suitably ornamented and the proportions and arrangement of the parts changed without departing from the scope of the invention.

I claim:

1. A combined leaf turner and book mark comprising a flexible pad with a friction surface on one face, a flexible strand secured at one end to one side of the pad, a catch at the other side of the pad for engagement by the strand, said friction surface acting to hold the pad in place when flat in a closed book, the strand acting as an indicator when projected from a book.

2. A combined leaf turner and book mark comprising a flexible pad with a friction surface on one face, a flexible strand secured at one end to one side of the pad, a catch at the other side of the pad for engagement by the strand, said friction surface acting to hold the pad in place when flat in a closed book, the strand acting as an indicator when projected from a book and a pendant on the strand which acts as a stop for the strand when the turner is secured on a finger.

In testimony whereof she affixes her signature.

GEORGIANA S. GIFFORD.
